GEORGE KEELER BAINBRIDGE AND SYDNEY WILLIAM REYNOLDS, OF RIPPON,
CALIFORNIA.

SANITARY CONTAINER.

Application filed December 6, 1926. Serial No. 152,860.

This invention relates to improvements in containers for edibles of that character which are intended to be eaten directly from the container by applying the mouth to one end of the container, and particularly represents an improvement over the device shown in our co-pending application for patent, filed December 10th, 1925, Serial No. 74,463. In this previous device a sanitary 10 wrapper for that end of the container intended to be applied to the mouth was provided in the form of a skirt surrounding the main body of the container at said end. This skirt was formed integral with the 15 blank from which the container was made and was folded down onto the blank before the latter was rolled. This not only called for a folding operation apart from the rolling operation, but necessitated tearing all 20 the thicknesses of the container and skirt completely through when unsealing the normally closed end of the container, in order to then separate the skirt from the body and allow the skirt to fall off. The above features made the container relatively expensive to manufacture and necessitated the use 25 of considerable strength to tear across the container when removing the sealing clip. This latter operation frequently caused the 30 container to become distorted and warped before being put to its final and proper use.

The principal object of the present invention therefore is to eliminate the above defective features by providing a sanitary 35 removable wrapper for the container so arranged that while formed integral with the blank from which the container is made, it eliminates the folding operation previously necessary, and does not require that the top 40 of the container shall be torn across when removing the sealing clip.

A further object of the invention is to provide an improved form of sealing clip particularly adapted to this form of container and so constructed that it may be 45 readily removed when desired without mutilating the container.

A further object of the invention is to produce a simple and inexpensive device 50 and yet one which will be exceedingly effective for the purpose for which it is designed.

These objects we accomplish by means of such structure and relative arrangement of

parts as will fully appear by a perusal of the following specification and claims.

In the drawings similar characters of reference indicate corresponding parts in the several views:

Fig. 1 is a side elevation of our improved container, sealed.

Fig. 2 is a view of the unrolled blank and extension from which the container and the sanitary wrapping are made.

Fig. 3 is a perspective of the removable sealing clip. 65

Referring now more particularly to the characters of reference on the drawings, the container is made from a rectangular blank or sheet 1 of suitable prepared paper. The length of this sheet is equal to that of the 70 finished container and its width is preferably about three times as great as the circumference of the finished container or so that the latter will have three complete turns or wrappings of paper in its make-up. 75 Along one side edge the sheet is formed with an integral extension 2 approximately half the height of the sheet. Weakening means such as a row of perforations 3 is placed along the vertical line of junction 80 between the sheet and the extension. The upper edge of the extension is aligned with and parallel to the upper edge of the sheet. The initial portion A of the lower edge of the extension, from the sheet 1 outwardly, is also parallel to said upper edge for a distance approximating one and a quarter 85 wrappings about the container. Said edge then slopes upwardly at an acute angle to the horizon as at B to join the outer side edge of the extension, which is very short. The total width or extent of the extension is sufficient to wrap about the container two or more times. A suitable adhesive 4 is placed on the inner surface of the sheet 90

1 adjacent that side edge from which the extension projects and to the side of the row of perforations away from said extension. 95

The sheet is rolled on a mandrel in a suitable manner so that the extension will be 100 outermost. As soon as the main sheet is rolled the adhesive is moistened or applied so that the outermost vertical edge of the sheet will adhere to the wrapping thereunder. The extension is then wrapped around 105 the container. The wrapping operation be-

ing completed the ends of the container are flattened or pinched together as at 5, and sealing clips are then applied to such ends. The lower sealing clip is a U-shaped member 6 of non-springy or bendable metal, which straddles the lower end wrappings and is suitably pressed into place and then preferably indented to engage the paper as indicated at 7. This clip is never intended to be removed, and is applied last. The upper clip 8 is also U-shaped to straddle the upper end wrappings (which include the outer end portion of the extension 2) and when applied to the container is indented as at 9 to grip the paper. This clip however also has central tabs 10 depending therefrom on both sides and normally lying adjacent the container. The clip 8 is applied first, while the container is still on the mandrel, so as to prevent the extension 2 from unwrapping. The contents of the container are placed therein from the lower end, which is then sealed by the clip 6.

When it is desired to open the container to consume or remove the contents, one or the other of the tabs 10 is pulled up and outwardly. This operation spreads the clip, causing it to be disengaged from the paper and allowing it to be removed to expose the contents. The extension member 2 not being secured to the main container wrappings along the top or down its side edge tends to unfold when thus freed from the clip, so that it may be then readily unwrapped for its full extent and torn off along the line of perforations 3. The main container then remains unharmed and intact and its outer and upper portion will be in a perfectly sanitary condition, since up to this time such portion has been covered and enclosed by the extension. The lower edge of the extension being cut straight for the initial portion of its extent, it insures that all the perforations will be normally covered so that there is no chance for accidental tearing along such perforations before it is desired to remove the extension. The sloping edge of the remainder of the extension forms a spiral when wrapped about the container, as shown in Fig. 1, this arrangement eliminating any tendency of said edge to bulge outwardly so that it could be readily torn, as would be the case if said edge were parallel to the axis of the container.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention what we claim as new and useful and desire to secure by Letters Patent is:

1. A container including a tubular body formed by a sheet of flexible material wrapped about itself, and an extension projecting from the outer side edge of the sheet wrapped completely about the body, said extension projecting downwardly from the top of the sheet to a point short of the bottom thereof.

2. A container including a tubular body formed by a sheet of flexible material wrapped about itself, an extension projecting from the outer side edge of the sheet wrapped completely about the body, said extension projecting downwardly from the top of the sheet to a point short of the bottom thereof, and adhesive material on the inner face of the sheet from top to bottom adjacent the junction of the extension therewith.

3. A container including a tubular body formed by a sheet of flexible material wrapped about itself, an extension projecting from the outer side edge of the sheet wrapped completely about the body, said extension projecting downwardly from the top of the sheet to a point short of the bottom thereof, means for causing the outermost portion of the sheet to adhere to the wrapping thereunder from top to bottom, and weakening means between the sheet and extension outwardly of the adhesive means.

4. A container including a tubular body formed by a sheet of flexible material wrapped about itself, an extension projecting from the outer side edge of the sheet wrapped completely about the body, said extension projecting downwardly from the top of the sheet to a point short of the bottom thereof, and weakening means along the junction of the sheet and extension.

5. A container including a tubular body formed by a sheet of flexible material wrapped about itself, an extension projecting from the outer side edge of the sheet wrapped completely about the body, said extension projecting downwardly from the top of the sheet to a point short of the bottom thereof, and weakening means along the junction of the sheet and extension, the lower edge of the extension extending parallel to the top of the sheet for a distance greater than one complete wrapping of said extension whereby to normally cover the weakening means.

6. A container including a tubular body formed by a sheet of flexible material wrapped about itself, an extension projecting from the outer side edge of the sheet wrapped completely about the body, said extension projecting downwardly from the top of the sheet to a point short of the bottom thereof, and adhesive means along the junction of the sheet and extension, a portion of

the lower edge of the extension sloping upwardly at an acute angle to a horizontal plane from adjacent the body toward the outer end of the extension.

5 7. A container including a tubular body formed by a sheet of flexible material wrapped about itself, an extension projecting from the outer side edge of the sheet wrapped completely about the body, said extension projecting downwardly from the top of the sheet to a point short of the bottom thereof, and a removable sealing clip to engage all the wrappings at the top.

10 8. A container comprising a tubular body, one end of which is pinched in, a U shaped sealing clip to be placed over such end to

engage the same, and a bendable tab depending from one side of the clip to serve as a means for spreading and prying up the clip.

9. A container comprising a tubular body, 20 a wrapping about the upper portion of said container and removably connected thereto only along the innermost vertical end of the wrapping, and means applied to the upper end of the container to seal the same and 25 normally prevent unfolding of the wrapping.

In testimony whereof we affix our signatures.
